(57) **CLAIM**

The ornamental design for a head for a wheel rim polishing tool, as shown and described.

DESCRIPTION

FIG. 1 is a perspective view of a wheel rim polishing tool showing the new design for a head therefore, the broken line indicating environmental structure but forming no part of the claimed design;

FIG. 2 is a side elevation view thereof, the wheel rim polishing tool being rotationally symmetric;

FIG. 3 is a plan view showing one end of the wheel rim polishing tool; and,

FIG. 4 is a plan view showing the opposite end thereof.
